UNITED STATES PATENT OFFICE.

TOMÁŠ BROŽ, OF PRAGUE, AUSTRIA-HUNGARY.

TOBACCO-PIPE.

1,074,489.

Specification of Letters Patent. Patented Sept. 30, 1913.

Application filed December 16, 1912. Serial No. 736,992.

To all whom it may concern:

Be it known that I, TOMÁŠ BROŽ, a subject of the Emperor of Austria-Hungary, residing in Prague, II, Bohemia, Austria-Hungary, have invented a certain new and useful Tobacco-Pipe, of which the following is a specification.

This invention relates to a tobacco pipe, the so-called sport pipe, constructed so that the smoke arrives cool and purified in the mouth, and the pipe does not get wet, burn or "bite," and the cleaning can be effected very quickly and easily.

A construction according to this invention is illustrated by way of example in the accompanying drawing in which—

Figure 1 is a longitudinal section through the whole pipe, Fig. 2 a longitudinal section through the head of the pipe, Fig. 5 shows the smoke tube in side elevation and Figs. 3, 4 and 6 are cross-sections.

Into the projection or neck 2 of the wooden pipe head or bowl α is inserted in a corresponding recess a slightly tapering metal tube 1 closed at the bottom and open at the top and provided at the bottom end with a vertical branch 3 from which branches off a small transmission tube 7 parallel to the tube 1. The tube 7 is closed at the upper end and connected to the tube 1 by means of an oblique hole 9. Into the tubular projection 3 projects the tubular piece 4 of the sheet metal insertion 5 lining the bottom of the bowl or chamber 6. Between the tube 1 and the small tube 7 is arranged an insulating layer 10. The tube 1 with the branch 3 and the small tube 7 forms one whole which, when the sheet metal insertion 5 with the tubular piece 4 is raised, can be withdrawn from the pipe head and inserted again.

Into the tube 1 is inserted the smoke tube 11 exactly fitting it. The said smoke tube is provided on its surface with a helical groove 14 terminating at the top in an annular recess 17 into which the hole 9 opens. The bottom end of the groove is connected by means of a hole 18 to the central hollow space 19 of the smoke tube, while a little higher, a hole 20 connects the axial bore 15 of the smoke tube to the groove 14, the said bore 15 projecting only as far as the hole 20. At the bottom end on the smoke tube is placed a metal sleeve 12 provided with two diametrical elongated recesses 21 and 22, one of which is wider than the other

to allow of the introduction of an interchangeable suction plug 13 closing the hollow space 19 at the bottom in an air-tight manner.

In smoking, the smoke passes from the tubular branch 3 into the transmission tube 7 and on arriving at the top, passes through the hole 9 into the annular recess 17 and thence into the helical groove 14. On arriving at the bottom, the smoke passes through the hole 20 into the bore 15 and thence into the mouthpiece.

Although the tobacco pipe described is small, and the branch 2 short, the smoke nevertheless arrives at the mouth cool and dry, as it has to travel a long distance, and the vapors of water settle on the walls of the transmission pipe 7 and groove 14 and trickle down to the suction plug 13, to which purpose the groove 14 is connected at the bottom end by means of the hole 18 to the suction plug 13. The moisture precipitated at the bottom of the tobacco chamber 6 passes direct into the suction plug 13.

The tobacco pipe described can be easily and quickly cleaned, as not only the smoke tube 11, but also the combined tube 1, 3, 7 can be withdrawn and is accessible at every point.

What I claim as my invention and desire to secure by Letters Patent is:—

1. In a tobacco pipe the combination of a bowl having a neck extension, a tapering tube closed at the lower end and adapted to be inserted into the neck extension, an extension branch on the lower end of the tapering tube, a transmission tube substantially parallel to the tapering tube and connected to the extension branch at the bottom and to the tapering tube at its upper end, a smoke tube adapted to be inserted in the tapering tube, a helical groove on the outside of the smoke tube and connected at its lower end to the interior of the smoke tube, a chamber in the lower end of the smoke tube and connected at its upper end to the helical groove, and a suction plug to close the lower end of the chamber in the lower end of the smoke tube.

2. In a tobacco pipe the combination of a bowl having a neck extension, a socket piece adapted to be inserted in the neck extension and comprising a tapering tube closed at the lower end, an extension branch on the lower end of the tapering tube and a transmission tube substantially parallel to the

tapering tube and connected at its lower end to the extension branch and to the tapering tube at its upper end, for the purpose set forth.

- 5 3. In a tobacco pipe the combination of a bowl having a neck extension, a tapering tube closed at the lower end and adapted to be inserted into the neck extension, an extension branch on the lower end of the
- 10 tapering tube, a transmission tube substantially parallel to the tapering tube and connected to the extension branch at the bottom and to the tapering tube at its upper end, a smoke tube adapted to be inserted in the
- 15 tapering tube a helical groove on the outside of the smoke tube and connected at its

lower end to the interior of the smoke tube, a chamber in the lower end of the smoke tube and connected at its upper end to the helical groove, and a sleeve provided with 20 diametrical slots of different widths and adapted to receive interchangeable suction plugs, said sleeve being adapted to close the bottom of the chamber in the lower end of the smoke tube.

25 In testimony whereof I have signed my name to this specification in the presence of two subscribing witnesses.

TOMÁŠ BROŽ.
